UNITED STATES PATENT OFFICE.

SILVIO COCANARI, OF ROME, ITALY, ASSIGNOR, BY MESNE ASSIGNMENTS, TO DU PONT-PATHE FILM MANUFACTURING CORPORATION, OF WILMINGTON, DELAWARE, A CORPORATION OF DELAWARE.

CUT-FILM CASE.

Application filed October 20, 1925, Serial No. 63,607, and in France October 29, 1924.

The known device for containing cut films which is commonly designated as "film pack" consists of a cardboard or metal box or container having at the middle a partition dividing the said box into two chambers which serve respectively for the exposed and the unexposed films. The said partition which forms an essential part of the said device, is so disposed that the film, after each exposure, 10 may be drawn from one chamber into the other by a suitable traction band. In order to provide for the said withdrawal of the films and to hold the sensitive surface properly against the exposing aperture, the said partition is metallic and comprises springs and cylindrical portions and the manufacture thereof is thus complicated and expensive. As a rule the known film packs contain a dozen films, and the case containing the same 20 cannot be used a second time after the said films have been exposed.

For this reason the cost of the said container will be a considerable factor in the total cost of the film pack, and this prevents 25 the manufacture of a package for instance of six films, for which the cost of the container would be prohibitive, since the reduction in the number of films will not bring about a corresponding reduction in the cost of the 30 container.

The present invention has for its object to eliminate these drawbacks, and relates to a containing case for cut films which is essentially characterized by the fact that it comprises firstly a case containing the cut film and intended for use only once, and secondly 35 an independent removable wall, provided with the required accessories and adapted for an indefinite use with successive cases.

In this manner the cost of the containers 40 will be much reduced and the removable partition, which is purchased once for all, may be of a more careful and substantial construction. The combination of the said case and the interchangeable wall will thus constitute 45 a device which is adapted for use with the known cameras and holders in the same manner as the film packs.

The following description refers to the accompanying drawings which are given by way of example and in which:

Fig. 1 is a perspective view of an envelope forming part of the device according to the invention.

Fig. 2 is a like view of a cut film of the type 55 employed with the same.

Fig. 3 is a perspective view showing the said envelope filled and folded.

Fig. 4 is a like view of an interchangeable 60 metallic wall serving to complete the envelope in order to form the container according to the invention.

Fig. 5 is a like view showing the insertion 65 of the interchangeable wall into the folded envelope.

Fig. 6 is an elevation of the rear face of the 70 filled envelope with parts broken away, and

Fig. 7 is a perspective view showing the 75 operation to be performed for the removal of the film through the exposing aperture of the envelope.

Fig. 1 shows an envelope or case 1 made of flexible black paper, provided with an exposing aperture 2 whose edges are strengthened by a cardboard frame 3, and with a slot 4 75 lined with black velvet 22 or suitable cloth for the exit of the traction bands. Each of the sensitive films 5 Fig. 2, is attached by means of a thin cloth band 6 to a sheet of black paper 7 provided with an extension consisting 80 of a long traction band 8 whose width is less than the width of the portion covering the sensitive film.

A suitable number of films are placed together and are inserted into the case 1 which 85 is then folded upon itself as shown in Fig. 3; the sensitive surfaces are turned towards the exposing aperture 2, and the traction bands 8 extend through the slot 4. A sheet of black paper 9 which resembles the sheets above 90 mentioned but which is not provided with a photographic film is superposed upon the whole series so as to be the first in contact with the aperture 2, and serves to protect the said film from the light when the device is loaded. 95

After the case containing the said film is folded, the device will resemble the known "film pack" in shape and size, but is as yet incomplete. It is necessary to add thereto a rigid central portion which is provided with 100 a lower cylindrical portion for changing the films and with suitable springs whereby the said films may be brought into the plane of exposure. The said central portion consists of an interchangeable metallic plate 10, Fig. 105 4; said plate comprises a flat portion which is applied against the back of the films in the rear of the exposing aperture, a lower cylin-

drical portion 11 co-operating with the angle of the folded case, and two springs 12 of steel wire between which is disposed the rear portion of the said envelope or case.

5 The film-holding device which is thus constituted by the folded case and the plate 10 which is disposed in the folded portion, may be inserted, Fig. 5, into a suitable holder comprising the two parts 13 and 14 hinged together, the springs 12 bear upon the part 13 and apply the plate 10 against the part 14, which is thus brought into contact with the exposing aperture 2 of the case; the pressure of the springs is transmitted solely to the 10 films to be exposed and without interfering with the portion of the case employed for containing the exposed films.

In the known film packs, each film can be withdrawn after it has been exposed, for purposes of separate development, but in this 20 event a part of the box must be opened—which is a difficult and complicated matter—and must then be closed by pasting, which is difficult to carry out in the proper conditions in 25 the dark.

In the device according to the present invention, the films can be removed at will with great facility, for this purpose through an opening 21 in the rear face of the case 1—seen 30 in elevation in Fig. 6—is passed a strip 15 which is drawn upon in the direction of the arrow *f*, it being secured to a flat ring 16 of cardboard or tin plate surrounding the black paper traction bands 8 which are of less width 35 than the films. An unexposed film occupies a position such as that of the film 17, whilst a film withdrawn after exposure is brought to the position of the film 18; in this position, the shoulder 19 of the black paper is in contact with the ring 16.

40 When the strip 15 is drawn in the direction of the arrow *f*, the ring 16 will draw out all the films occupying the position of the film 18, i. e. all the exposed films, and these will 45 move to a point about midway in the aperture 2, Fig. 7. The ring 16 will have no action upon the unexposed films such as 17.

The films which are brought into the position of the film 20, Fig. 7, can be readily removed through the aperture 2 without any 50 removal of the outer envelope. After this operation, it will be unnecessary to bring back the strip 15, for the latter will be drawn back by the shoulder 19 of the first film withdrawn 55 during the succeeding operation.

Among other advantages, and in addition to the reduced cost of construction, the film case according to the invention will have the minimum thickness before as well as after the 60 exposure of the films, since the interchangeable metallic plate is utilized only when the case is disposed in the holder. When apart from the holder, the said film pack is in reality only a folded case or envelope containing 65 a certain number of sheets of paper and films.

Obviously, the constructional arrangements hereinbefore set forth are given solely by way of example and for the proper comprehension of the invention, and are in no 70 limitative nature.

Having now described my invention, what I claim as new and desire to secure by Letters Patent is:

1. Packing for cut films provided with traction bands and adapted for use with the usual holders having a front wall and a rear wall and comprising a pliable envelope designed for use only once and adapted to contain the films and their traction bands, the part of said envelope adapted to contain the blank films being provided with an exposing aperture, and an independent removable plate designed for indefinite use adapted to be inserted even in the daylight between the two parts of said envelope adapted to contain respectively the blank films and the traction bands, when said two parts are folded against each other, and means to cause said plate to press the blank films against said exposing aperture.

2. Packing for cut films provided with traction bands and adapted for use with the usual holders having a front wall and a rear wall and comprising an envelope made of a flexible and cheap material designed for use only once and adapted to contain the films and their traction bands, the part of said envelope adapted to contain the blank films being provided with an exposing aperture, and an independent removable plate designed for indefinite use adapted to be inserted even in the daylight between the two parts of said envelope adapted to contain respectively the blank films and the traction bands, when said two parts are folded against each other, and means to cause said plate to press the blank films against said exposing aperture.

3. Packing for cut films provided with traction bands and adapted for use with the usual holders having a front wall and a rear wall and comprising an envelope of opaque paper designed for use only once and adapted to contain the films and their traction bands, the part of said envelope adapted to contain the blank films being provided with an exposing aperture, and an independent removable plate designed for indefinite use adapted to be inserted even in the daylight between the two parts of said envelope adapted to contain respectively the blank films and the traction bands, when said two parts are folded against each other, and means to cause said plate to press the blank films against said exposing aperture.

4. Packing for cut films provided with traction bands and adapted for use with the usual holders having a front wall and a rear wall and comprising an envelope made of a flexible and cheap material designed for use only once and adapted to contain the films

and their traction bands, the part of said envelope adapted to contain the blank films being provided with an exposing aperture, a rigid strengthening border for the edges

5 of said exposing aperture, and an independent removable plate designed for indefinite use adapted to be inserted even in the daylight between the two parts of said envelope adapted to contain respectively the blank 10 films and the traction bands, when said two parts are folded against each other, and means to cause said plate to press the blank films against said exposing aperture.

5. Packing for cut films provided with 15 traction bands and adapted for use with the usual holders having a front wall and a rear wall and comprising an envelope made of a flexible and cheap material designed for use only once and adapted to contain the films 20 and their traction bands, the part of said envelope adapted to contain the blank films being provided with an exposing aperture, a cardboard strengthening border for the edges of said exposing aperture and an independent removable plate designed for indefinite use adapted to be inserted even in the daylight between the two parts of said envelope adapted to contain respectively the blank 25 films and the traction bands, when said two parts are folded against each other, and means to cause said plate to press the blank films against said exposing aperture.

6. Packing for cut films provided with traction bands and adapted for use with the usual holders having a front wall and a rear 30 wall and comprising an envelope made of a flexible and cheap material designed for use only once and adapted to contain the films and their traction bands, the part of said envelope adapted to contain the blank films being provided with an exposing aperture, an independent removable rigid plate designed for indefinite use adapted to be inserted even in the daylight between the two parts of said envelope 35 adapted to contain respectively the blank films and the traction bands, when said two parts are folded against each other and springs provided on said plate and adapted to bear on one side upon one wall of said holder and whereby the blank films contained on the other side in said envelope may be constantly pressed against said exposing aperture.

7. Packing for cut films provided with traction bands and adapted for use with the usual holders having a front wall and a rear wall and comprising an envelope made of a flexible and cheap material designed for use only once and adapted to contain the films 50 and their traction bands, the part of said envelope adapted to contain the blank films being provided with an exposing aperture, an independent removable rigid plate designed for indefinite use adapted to be inserted even in the daylight between the two

parts of said envelope adapted to contain respectively the blank films and the traction bands, when said two parts are folded against each other, and springs provided near the side edges of said plate and adapted to bear 70 on one side upon one wall of said holder and whereby the blank films contained on the other side in said envelope may be constantly pressed against said exposing aperture, the distance between said springs being 75 such that the traction bands containing part of said envelope may be lodged between them when said envelope is folded.

8. Packing for cut films provided with traction bands and adapted for use with the usual holders having a front wall and a rear wall and comprising an envelope made of a flexible and cheap material designed for use only once and adapted to contain the films and their traction bands, the part of said envelope adapted to contain the blank films being provided with an exposing aperture, and an independent removable plate designed for indefinite use adapted to be inserted even in the daylight between the two 85 parts of said envelope adapted to contain respectively the blank films and the traction bands, when said two parts are folded against each other, and means to cause said plate to press the blank films against said exposing aperture, the edge of said plate which is to be inserted into the fold of the envelope consisting of a cylindrical part upon which the films may be smoothly shifted from one part 90 of the folded envelope to the other. 100

9. Packing for cut films provided with traction bands and adapted for use with the usual holders having a front wall and a rear wall and comprising an envelope made of a flexible and cheap material designed for use 105 only once and adapted to contain the films and their traction bands, the part of said envelope adapted to contain the blank films being provided with an exposing aperture, an independent removable plate designed for indefinite use adapted to be inserted even in the daylight between the two parts of said envelope adapted to contain respectively the blank films and the traction bands, when said two parts are folded against each other, 110 means to cause said plate to press the blank films against said exposure aperture and means whereby the exposed films may be removed out of said envelope through said exposing aperture by drawing said exposed films in a direction opposite to that in which said films are shifted after exposure. 115

10. Packing for cut films provided with traction bands and adapted for use with the usual holders having a front wall and a rear 120 wall and comprising an envelope made of a flexible and cheap material designed for use only once and adapted to contain the films and their traction bands, the part of said envelope adapted to contain the blank films 125 130

being provided with an exposing aperture, an independent removable plate designed for indefinite use adapted to be inserted even in the daylight between the two parts of said envelope adapted to contain respectively the blank films and the traction bands, when said two parts are folded against each other, means to cause said plate to press the blank films against said exposing aperture, a movable stop piece normally disposed in the traction bands containing part of said envelope and against which the exposed films are caused to bear when they are shifted away from the exposing aperture after exposure, and means whereby said stop piece may be shifted back towards said exposing aperture together with the exposed films.

11. Packing for cut films provided with traction bands and adapted for use with the usual holders having a front wall and a rear wall and comprising an envelope made of a flexible and cheap material designed for use only once and adapted to contain the films and their traction bands, the latter having a smaller width than the former, the part of said envelope adapted to contain the blank films being provided with an exposing aperture, an independent removable plate designed for indefinite use adapted to be inserted even in the daylight between the two parts of said envelope adapted to contain respectively the blank films and the traction

bands, when said two parts are folded against each other, means to cause said plate to press the blank films against said exposing aperture, a ring adapted to surround the traction bands and normally disposed at the outer end of the traction bands containing part of said envelope and a traction strip secured at one end to said ring and the other end whereof extends out of said envelope and whereby said ring may be shifted towards said exposing aperture together with the exposed films.

12. A film pack holder, comprising a tubular film-receiving envelope provided with an exposure aperture and adapted to be folded upon itself and means insertable between the folded parts of the envelope to yieldingly press films in the envelope against the exposure aperture.

13. A film pack holder, comprising a relatively easily destructible tubular film-receiving envelope having an exposure aperture substantially half the length of the envelope, said envelope adapted to be folded upon itself, and relatively indestructible means removably arranged between the folded parts of the envelope to yieldingly press parts of the films in the envelope against the exposure aperture.

In testimony whereof I have signed my name to this specification.

SILVIO COCANARI.
